UNITED STATES PATENT OFFICE.

RICHARD HENRY ROBERTS, OF HENDERSON, AUCKLAND, NEW ZEALAND, ASSIGNOR TO ANGLE BRACE COLLAPSIBLE BOX COMPANY LIMITED, OF AUCKLAND, NEW ZEALAND, A CORPORATION OF NEW ZEALAND.

BRACE FOR CASES AND THE LIKE CONTAINERS.

Application filed May 21, 1923. Serial No. 640,562.

To all whom it may concern:

Be it known that I, RICHARD HENRY ROBERTS, citizen of the Dominion of New Zealand residing at "Farnley Tyas", Te Atatu, Henderson, in the Provincial District of Auckland, New Zealand, have invented an Improved Brace for Cases and the like Containers, of which the following is a specification.

10 This invention relates to braces, used on containers such as boxes, cases and the like, and has for its object the provision of an improved form of brace, capable of being easily adjusted and secured on a container 15 for the purpose of strengthening and holding the latter together, and which is also capable of being detached or removed with ease and without trouble and damage, in order that it may be re-used. The special 20 form of brace to be herein described, is specially adapted for use on boxes or containers capable of being knocked down and returned in a collapsed condition, and may be used 25 as a means of securing a lid on a container without the aid of nails or the like.

According to the invention the improved brace comprises a frame member of wire or other suitable flexible material, which surrounds that portion of the container it is desired to reinforce or strengthen.

30 The brace is made large enough to enable it to be passed on the container and over projections therefrom, after which the brace is twisted and tightened by swinging opposite sides or portions in reverse directions, thereby causing the slack in the brace to be taken up and the latter to be strained around the container and to serve as a binder thereon.

40 After the brace has been tightened or strained around the container as much as possible, it is prevented from slackening off by securing the opposite sides or portions to the container against return movement.

45 In practice preferably one side or portion of the brace will be fixed to the container, the slack in the brace being taken up, and the brace tightened by swinging the side or portion of the brace opposite the fixed side.

50 The improved brace and convenient means, for facilitating the twisting and tightening of same are shown in the accompanying drawing in conjunction with which the invention will be further described:—

55 Figure 1 is a plan view and

Figure 2 a side view of a case, provided with the improved brace, and showing same as it appears before being tightened, while

Figure 3 is a plan view and

Figure 4 a side view of the same case, 60 showing the improved brace as it appears when tightened.

In the drawing 1 represents a case of ordinary construction and 2 the improved brace which is endless, and formed from 65 wire or other material having the necessary flexibility and strength.

A portion of the brace 2 in this instance the bottom of the latter, is accommodated in a groove 3 formed either in the case 1 70 or as illustrated in a strip 4 of material fixed against movement on the case. Preferably the groove 3 is formed at an angle other than a right angle to the length of the case. Instead of being accommodated in 75 the groove 3, the bottom of the brace can bear against a stop or stops on the container, so as to resist twisting of the brace.

The directly opposite portion of the brace 2 in this instance the top thereof, is engaged 80 in or caused to lie in a groove 5 formed in a strip 6 of material centrally pivoted as at 6^a to the case. The strip 6 is provided to facilitate straining or tightening the brace 2, but the latter can be tightened without said strip 6.

The brace 2 is given a shape similar to the outer cross sectional shape of the case and is made large enough to be passed on the latter and over any projections therefrom, such as reinforcing battens and the like, in order that its opposite portions may be placed in the grooves 3 and 5 at opposite sides or portions of the case. 90

When this has been done the brace 2 will 95 occupy or be in the position shown in Figures 1 and 2 with its portions which connect the portions engaged in the grooves 3 and 5 parallel with each other.

In this position the brace 2 is comparatively slack, that is to say it has not been tightened or strained around the case. 100

To effect the tightening of the brace around the container the centrally pivoted strip 6 is swung on its pivot 6^a as far as possible in 105 the direction indicated in Figure 1 in order to bring it to a position similar to that shown in Figure 3, said strip being secured against return movement on its pivot 6^a under the influence of the twisted brace 2, by 110

fastenings, preferably screws 7 inserted in the case.

The action of swinging the strip 6 on its pivot 6^a effectually takes up all the slack in the brace 2 and causes same to be strained around the case, the securing of said strip 6 in the position shown in Figure 3 maintaining the brace 2 in its strained or taut condition with the portions which connect the portions engaged in the grooves 3 and 5 running in opposite directions or crossing each other as shown in Figure 4.

It will be obvious from the foregoing that more than one brace can be used on a single case if circumstances necessitate it, also that in order to ensure the brace 2 being tightened quickly and to the required extent both of the strips 4 and 6 can be centrally pivoted and provided with fastening means 7, so as to be both capable of being swung or moved to tighten the brace, and further that it will be possible to tighten the brace on the container by twisting without the aid of the strips 4 and 6.

25 What I do claim and desire to obtain by Letters Patent of the United States of America is:—

1. A brace for containers, comprising, a flexible frame member adapted to be passed on a container and to be tightened thereon, by having opposite sides thereof swung in reverse directions, and means for securing said opposite sides to the container in positions wherein the brace is strained around the container.

2. A brace for containers, comprising, a flexible frame member adapted to be passed

on a container, and at least one grooved member secured to the container and in which portions of the frame member are engaged; for enabling said frame member to be tightened on the container.

3. A brace for containers, comprising, a flexible frame member adapted to be passed on a container and to be placed so that a portion of the brace is held against twisting movement; and a member containing a groove for accommodating another portion of the frame member and centrally pivoted to the container, for enabling said frame member to be twisted and tightened on the container by turning movement of said pivoted member.

4. A brace for containers, comprising, a flexible frame member having a shape similar to the outer cross sectional shape of a container on which it is to be used and adapted to be passed on the container, a member fixed to the container and having a groove which receives a portion of said frame member, a second member containing a groove for securing the portion of the frame member opposite to that portion engaged in the fixed member and centrally pivoted on the container, and means for securing the centrally pivoted grooved member in a position which holds the brace tightened around the container.

In testimony whereof I have signed my name to this specification.

RICHARD HENRY ROBERTS.
